SURGICAL RETRCTOR

Henry M. Jackson, Salt Lake City, Utah

Application February 25, 1952, Serial No. 273,176

2 Claims. (Cl. 128—20)

1

This invention relates to surgical instruments, and particularly to the type of instrument known as a retractor.

Retractors are commonly used in surgery to maintain an incision open during an operation, so that the surgeon may work unhampered and with free access to the opening. Existing constructions are well adapted to surgical operations on certain parts of the body, for example, the rectum, but I have found none adapted to thyroid and to other surgery of the neck and generally similar parts of the body where the particular body contour presents special problems.

A principal object, then, of this invention is to provide a surgical retractor peculiarly adapted to neck surgery and the like, one which will effectively accomplish the purpose sought, without itself interfering with free access of the surgeon to the operative opening, and one which can be quickly and easily applied and removed and adjusted for any given instance of use.

Most surgical retractors embody a pair of jaws, one of which is adjustably mounted relative to the other for separation over a required distance and for anchorage in any given adjusted position. The jaws are equipped with flesh-gripping formations of one kind or another extending therefrom.

The instrument of the invention is similar in some respects to existing constructions, but introduces new structural features and relationships, which, despite their simplicity, solve problems long existing in certain types of surgery, especially surgery of the neck.

In accordance with the invention, a pair of elongate jaws, equipped with flesh retraction members projecting laterally therefrom in mutual opposition, are pivoted to and form articulative extensions of respective arms, which, themselves, extend laterally from and are each slideably mounted on an elongate slideway, preferably a bar of polygonal cross-section which precludes rotation of the arms thereon. The jaws are pivoted on respective axes which are substantially parallel with the slideway, so that the body of the retractor will drop down beside the neck, or other body part concerned, and lie in substantial parallelism therewith closely thereagainst and well below the level of the open incision. Thus, the margins of the incision are effectively and positively held in retracted position, providing a widely opened area for surgical manipulations, while the retracting instrument, itself, in no way obstructs or otherwise interferes with the activities of the surgeon.

2

Further objects and features of the invention will become apparent from the following detailed description of preferred specific embodiments thereof, as illustrated in the accompanying drawing.

In the drawing:

Fig. 1 represents a top plan view of the retractor of the invention in position for retracting the margins of a customary neck incision in thyroid surgery;

Fig. 2, a similar view, but showing the position assumed by the retractor in accomplishing and maintaining a complete retraction of the margins of the incision for surgical purposes;

Fig. 3, a transverse section taken along the line 3—3 of Fig. 2, showing how the retractor hangs down against the neck and out of the way of the surgeon;

Fig. 4, a bottom plan view of the retractor per se;

Fig. 5, a fragmentary elevation looking from the right in Fig. 4;

Fig. 6, a section taken in the line 6—6 of Fig. 5;

Fig. 7, a fragmentary view corresponding generally to that of Fig. 6, but illustrating an embodiment equipped with somewhat different jaws, for more general use, as for example, in connection with vein ligature; and

Fig. 8, a fragmentary view corresponding generally to that of Fig. 5, but with respect to the embodiment of Fig. 7.

Referring to the drawing:

The instrument shown in Figs. 1 through 6 is adapted primarily for thyroid surgery, as illustrated in Figs. 1 and 2.

In the form illustrated, it comprises a slideway bar 10, shown as having a square cross-section and headed ends 10a. Slideably mounted on such slideway bar between the headed ends 10a, and projecting laterally from the bar, is a pair of jaw-carrying arms 11 and 12, the mounting being preferably accomplished by means of respective end portions 11a and 12a formed as sleeves for fitting over the slideway bar in close fitting fit. Respective set screws 13 are advantageously provided for positively locking the arms 11 and 12 in any given relative positions on the slideway bar.

Pivotal secured to the outer ends of the arms 11 and 12, as by means of pins 14 and 15, are respective retractor jaws 16 and 17, constituting an operative pair of jaws for tissue retractive purposes. Such jaws 16 and 17 are preferably formed with respective opposing sets of depending, curved teeth, 16a and 17a, which are ar-

ranged in mutually spaced relationship along the length of the outer end portions of the jaws. As so formed and arranged, the teeth 16a and 17a correspond to retractor teeth heretofore used with conventional retractor instruments, and nothing new is claimed for their use as such.

Not conventional, however, is the pivotal mounting of the jaws 16 and 17 on the respective arms 11 and 12, which, in combination with the retractor teeth or other grasping formations extending laterally of the jaws proper, enable the instrument to accomplish the desired results. It should be noted that the pivot axes represented by the pins 14 and 15 are aligned end-to-end, and are parallel with the slideway bar 10. Thus, the instrument provides for free swinging, relative movement between the jaws 16 and 17 and the assembly of slideway bar 10 and carrying arms 11 and 12, about the pivot pins 14 and 15 as a longitudinally extending center.

This feature is of great importance in the use of the instrument, as can be easily seen from the showing of Fig. 3, since it enables the slideway and carrying arms to hang down against the neck, out of the way of the surgeon, during thyroid or similar surgery.

Contributing materially to the functional effectiveness of the retractor in this connection, is the fact that both carrying arms 11 and 12 are slideable relative to the slideway bar 10. As so constructed, the slideway bar and carrying arms may be freely adjusted in position relative to one another and to the neck of the patient, prior to and following the positioning of the jaws 16 and 17 in the incision 18; Figs. 1 and 2.

When the jaws are manually forced apart to properly retract skin and other tissues at the margins of the incision, as shown in Fig. 2, the set screws 13 are usually tightened to positively insure against slippage of the arms on the slideway bar during surgery. This is not always necessary, however, since the tendency for the retracted tissues to return to their normal positions will exert pressure on the jaws, which will normally cause the sleeves 11a and 12a to bind tightly against slippage on the slideway bar.

It should be noted that, due to the unique construction of the instrument of the invention, completely effective retraction of the tissues concerned is had, and no parts of the instrument are in a position to in any way impede or obstruct the surgical procedure. Furthermore, the instrument is quickly and easily applied and removed.

While the retractor of the invention is especially adapted for thyroid surgery, it may be employed wherever its special structural attributes render it advantageous.

For other retractive uses, it may be necessary or desirable to employ jaws having laterally ex-

tending grasping members of different formation than the teeth 16a and 17a. Thus, as illustrated in Fig. 7, jaws having elongate and opposingly curved loop members 20, instead of a series of sharp fingers, may be employed for various surgical purposes, such as vein ligature in the legs.

Whatever the formation of the retractor jaws, however, as dictated by the particular use desired for the instrument, the distinctive structural features of the instrument, as outlined above, render it capable of achieving results heretofore unrealized in surgical techniques.

Whereas this invention is here illustrated and described with respect to particular preferred forms thereof, it should be realized that various changes therein and various other forms may be resorted to by those skilled in the art, on the basis of the teachings hereof, without departing from the scope of the claims which here follow.

20 I claim:

1. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws.
- 25 2. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws.
- 30 3. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws; and by the further fact that both of said retractor arms are slideable on the slideway bar relative to it and to each other.
- 35 4. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws; and by the further fact that both of said retractor arms are slideable on the slideway bar relative to it and to each other.
- 40 5. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws; and by the further fact that both of said retractor arms are slideable on the slideway bar relative to it and to each other.
- 45 6. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws; and by the further fact that both of said retractor arms are slideable on the slideway bar relative to it and to each other.
- 50 7. A surgical retractor made up of an elongate slideway bar, and a pair of elongate jaw-carrying arms mounted in mutually opposed relationship on and extending laterally from and transversely to the said slideway bar, said retractor being characterized by the fact that the jaws form longitudinal extensions of the respective arms, and are pivoted in free-swinging relationship to the free ends of said arms on axes which are substantially aligned end-to-end and substantially parallel with the slideway bar; and by the further fact that flesh-retracting members extend laterally from and transversely of the jaws; and by the further fact that both of said retractor arms are slideable on the slideway bar relative to it and to each other.
